UNITED STATES PATENT OFFICE

2,004,443

LENS

Rudolph Kovac, Chicago, Ill., assignor to American Automatic Devices Co., Chicago, Ill., a corporation of Illinois

Application September 14, 1934, Serial No. 743,964

3 Claims. (Cl. 88—82)

My invention relates to lenses and particularly to combination projector and reflector lenses, and it has for its object the provision of a new and improved form and arrangement of cooperating parts whereby the lamp in which the lens is used shall be effective for projecting a distinct pencil of light from the source of light in the lamp along the axis of the lens while at the same time being so illuminated as to have high visibility from points far removed angularly from the axis of the lens and particularly from points directly or substantially at right angles to the axis of the lens. It is another object of my invention to provide a construction of the type named such that the lens shall be very effective as a reflector for sending rays backwardly to points near the source of light when illuminated from points outside of the lamp, as from the headlights of an approaching car, effective in this manner with respect to light from various angles relatively to the axis of the lens and particularly with respect to light from a source either substantially in the line of the axis or substantially at right angles to the axis of the lens.

It is one of the objects of my invention to provide an arrangement by virtue of which effective projection of light may be effected through the lens and effective reflection shall be attained from the lens without the necessity for having the lens manufactured upon a precision basis, whereby a product manufactured upon a commercial scale with comparatively high tolerances as to size and shape shall be acceptable for the purposes for which it is designed.

It is another object of my invention to improve devices of this type in sundry details herein-after pointed out. The preferred means by which I have accomplished my several objects are illustrated in the drawing and are herein-after specifically described. That which I believe to be new and desire to cover by Letters Patent is set forth in the claims.

In the drawing—

Fig. 1 is a central vertical section through a preferred form of lamp comprising my improved lens;

Fig. 2 is a back face view of my lens; and

Fig. 3 is a cross sectional view taken substantially at line 3—3 of Fig. 1.

Referring now to the several figures of the drawing, in which corresponding parts are indicated by the same reference characters, 10 indicates a casing of sheet metal in the form of a cup having a sleeve 11 mounted radially in position in the side wall, with a spacing sleeve

12 secured on the outer end of the sleeve 11 for spacing the casing 10 from a bracket 13 to which the casing is secured by means of a nut 14 mounted on the lower end of a threaded sleeve 15 formed with or rigidly connected to the sleeve 11. An electric light bulb 16 is secured in any approved manner in the upper end of the sleeve 11 and having electrical connection with a lead 17 for energization of the filament of the bulb from any suitable source of electrical energy.

Upon its side wall portions opposite the bolt 16, the casing 10 is provided with brackets 18 serving as the support for a lens 19 which is removably secured in position in the front end of the casing 10 by means of a split ring 20 co-operating with an inwardly turned flange 21 at the forward edge of the casing.

As is best shown in Fig. 1, the lens 19 is formed concavo-convex, with its outer or convex face having a continuous curvature, the lens in its preferred form comprising slightly less than a half of a prolate spheroid. The inner or concave face of my improved lens is arranged in concentric steps at its middle portion comprising substantially plane annular zones 22 alternating with substantially frusto-conical annular zones 23, with a plane circular zone 24 at its middle point. At its outer edge portion outside of the stepped formation, the inner face of the lens comprises a series of diverging ribs 25, each of which is defined by faces standing at substantially right angles to each other. In the arrangement shown the portion arranged in concentric steps comprises substantially the middle two-thirds of the lens diametrically thereof. In the arrangement shown the ribs 25 are positioned at an angle of approximately 30° from the axis of the lens.

I have found in practice in the use of my device that when the bulb 16 is illuminated by a current through the filament a distinct pencil of light is projected forwardly through the lens with such pencil spreading sufficiently that the ray is clearly visible not only from directly in front of the lens but also from points located at some little distance transversely from the axis of the lens. With the bulb 16 illuminated, the lens 19 is clearly visible directly from the side at points located at considerable distances from the lamp at right angles to the axis of the lens. I have found also in practice that when the bulb 16 is burnt out a ray of light from an external source falling upon the lens is reflected backwardly to its source with sufficient spread

for enabling one in the neighborhood of the source of light to detect easily the presence of the lens and to determine readily its color. This reflection backwardly to the source of a light 5 located externally is particularly effective when such external light strikes the lens either directly from the front or directly from one side.

I have found in practice in the use of my improved lens that there is an effective cooperation 10 between the stepped portions of the lens and the ribbed portions of the lens for both the projection and the reflection of light whereby the device is very effective for the purpose for which it is designed.

15 While I prefer to employ the form of device as shown in my drawing and as above described, it is to be understood that my invention is not limited to the form shown except so far as the claims may be so limited by the prior art.

20 I claim:—

1. A concavo-convex lens having its convex side smooth, and having its concave side at its middle portion arranged in concentric steps and provided at its outer portion with diverging ribs

each positioned at an angle of not more than approximately 30° from the axis of the lens.

2. A concavo-convex lens having its convex side smooth, and having its concave side at its middle portion arranged in concentric steps 5 and provided at its outer portion with diverging ribs each positioned at an angle of not more than approximately 30° from the axis of the lens, each of said ribs being defined by faces standing at an angle of approximately 90° with respect to each other.

3. A concavo-convex lens having its convex side smooth, and having its concave side at its middle portion arranged in concentric steps 15 transversely positioned with respect to the axis of the lens and comprising substantially plane zones alternating with substantially frusto-conical zones, the outer portion of said concave side being provided with diverging ribs each positioned at an angle of not more than approximately 30° from the axis of the lens, each of said ribs being defined by faces standing at an angle of approximately 90° with respect to each other.

RUDOLPH KOVAC.
